United States Patent Office

Des. 219,976
Patented Feb. 23, 1971

219,976

COMBINATION BATHTUB AND SHOWER UNIT

Merritt W. Seymour, 115 Carol Lane,
Toledo, Ohio 43615

Filed Dec. 11, 1969, Ser. No. 20,457

Term of patent 14 years

Int. Cl. D23—02

U.S. Cl. D23—49

FIG. 1 is a front perspective view of a combination bathtub and shower unit;

FIG. 2 is a front elevational view thereof;

FIG. 3 is a top plan view thereof; and

FIG. 4 is a cross sectional view taken on line 4—4 of FIG. 2.

I claim:

The ornamental design for a combination bathtub and shower unit, substantially as shown.
